CLAIM

I claim the ornamental design for a straw sterilizer, as shown and described.

DESCRIPTION

FIG. 1 is a top, rear, right perspective view of a straw sterilizer in a closed configuration, showing my new design. FIG. 2 is a right side elevation view thereof.

FIG. 3 is a left side elevation view thereof.

FIG. 4 is a top plan view thereof.

FIG. 5 is a bottom plan view thereof.

FIG. 6 is a front elevation view thereof.

FIG. 7 is a rear elevation view thereof.

FIG. 8 is a right side elevation view of the straw sterilizer of FIG. 1 in an open configuration.

FIG. 9 is a left side elevation view thereof.

FIG. 10 is a top plan view thereof.

FIG. 11 is a bottom plan view thereof.

FIG. 12 is a front elevation view thereof.

FIG. 13 is a rear elevation view thereof; and,

FIG. 14 is a top, rear, right, perspective view thereof.

The broken lines in the drawings illustrate portions of the reusable straw sterilizer which form no part of the claimed design.
